UNITED STATES PATENT OFFICE.

RAUL R. MORENO, OF SOUTH BETHLEHEM, PENNSYLVANIA.

HYDRAULIC VARIABLE-SPEED GEAR.

1,159,980.

Specification of Letters Patent.

Patented Nov. 9, 1915.

Application filed June 4, 1913. Serial No. 771,662.

To all whom it may concern:

Be it known that I, RAUL R. MORENO, a lieutenant in the Argentina Navy, and a citizen of Argentina, and a resident of South 5 Bethlehem, in the county of Northampton and State of Pennsylvania, have made certain new and useful Improvements in Hydraulic Variable-Speed Gears, of which the following is a specification.

10 My invention relates to improvements in hydraulic speed gears, and it consists in the combinations, constructions, and arrangements herein described and claimed.

An object of my invention is to provide a 15 hydraulic speed gear of relatively high efficiency.

A further object of my invention is to provide, in a hydraulic speed gear, a novel form of mechanism for driving the pump 20 pistons and also for regulating the length of stroke of the pump pistons.

A further object of my invention is to provide a device in which the regulation of the stroke of the pump pistons is accomplished by the same mechanism which accomplishes the reversal of the liquid through the speed gear thereby reducing the parts which are required to be handled in the operation of the device.

30 A further object of my invention is to provide an improved form of valve operating mechanism.

Other objects and advantages will appear in the following specification, and the novel 35 features of the invention will be particularly pointed out in the appended claims.

My invention is illustrated in the accompanying drawings forming part of this application in which—

40 Figure 1 is a view showing the speed gear connected on one side with a prime mover such as an electric motor and on the other with a hydraulic motor, Fig. 2 is a section along the line 2—2 of Fig. 3, Fig. 3 is a horizontal longitudinal section through the device, Fig. 3^a is a section along the line 3^a—3^a of Fig. 3, Fig. 4 is a section along the line 4—4 of Fig. 3, Fig. 5 is a perspective view of a rotary valve, Fig. 6 is a side view of a 45 slidable frame and means for moving the same, Fig. 7 is a section along the line 7—7 of Fig. 3, and Fig. 8 is a side view of one of the screw shafts.

In carrying out my invention I provide an

exterior frame 1 having an integral end 55 portion 2 (see Fig. 3) provided with an extension 3 which serves as a housing for the roller bearings 5 of the main drive shaft 6. The shaft 6 is provided with a threaded portion 6^a arranged to receive a thrust collar 7, 60 ball bearings 8 being provided for taking up the end thrust of the collar.

The inner end of the main drive shaft 6 is provided with a head 9, thrust bearings 10 being provided adjacent to the head. 65 The head 9 is provided with ears or flanges 9^a between which is disposed a plate 11, the latter being pivotally connected with the ears or flanges 9^a by means of the pin 12 (see Figs. 3 and 7). The plate 11 extends 70 through an opening 13^x of a plate 13. This plate is provided with ball bearings 13^y on either side. The plate 13 and the ball bearings 13^y are carried in a slidable frame formed by the annular members 14, and 16 75 which are secured together by means of bolts or screws 17 which pass through the intermediate member 15, as clearly shown in Fig. 3. This plate has a movement with respect to the frame in which it is carried at right 80 angles to the axis of the shaft 6. The annular member 16 is provided with a reduced extension 16^x about which is disposed a ring 18 having an integral gear 19 and a worm gear 20. The ring 18 is provided with ball 85 bearings 18^x so as to turn easily on the extension 16^x. A nut 19^x is provided for holding the ball bearings in position.

One end of the plate 11 is provided with an extension 11^a having a squared end 11^b. 90 The portion 11^a is provided with a hemispherical bearing head 11^c which is secured in place within a sleeve 21 by means of a ring 22. The sleeve has roller bearings 23 for supporting an exterior ring 24. The 95 latter is provided with a series of plunger rods 25 which are loosely secured to the ring by ball and socket connections such as that shown at 26. A piston or plunger 27 is provided for each plunger rod 25 and these 100 plungers are arranged to reciprocate in cylinders 28 formed by boring the casting in the manner shown in Fig. 2, screw plugs 29 being provided for closing the ends of the bores. Passages such as those shown at 30 105 in Figs. 2 and 3 lead from the end of the cylinders. These passages are controlled by a valve in the manner hereinafter described.

Referring to Figs. 3 and 4 it will be seen that there is an annular chamber 31 which is in constant communication with a pipe 32. An annular chamber 33 is in constant communication with a pipe 34.

In Fig. 5 I have shown the valve by means of which the fluid is directed toward and away from the passages 30. This valve is provided with a cylindrical body portion 35 having an annular channel 36 arranged to register with the chamber 33. Bearing rings 35' are provided on the periphery of the cylindrical body portion 35. On one side of the valve is an extension 37, which is provided with a substantially semicircular channel 38, communicating with the annular channel 36. The body portion 35 also has an integral ring 39, which is provided with an interior bearing ring 39'. The ring 39 is joined to the extension 37 by means of radially extending walls 40 which serve to inclose the ends of the semicircular channel 38. The central portion of the member 35 is provided on one side with a pair of lugs 41 having plane opposed sides which are faced with anti-friction bearing strips 41'. Oil openings 42 are provided as shown in Figs. 3 and 5. Thrust bearings 43 which are regulated by set screws 44 are provided for the valve.

On the opposite side of the plungers from the plate 11 is a similar plate 11' having parts 11^a and 11^b similar to the parts 11^a and 11^b. The plate 11' passes through a plate 13' similar to the plate 13 and is mounted in a slidable frame having parts 14', 15' and 16' similar in their nature to the parts 14, 15 and 16. The plate 11' is provided with a tongue or extension 45 arranged to enter between the lugs 41 of the body portion 35 of the valve. Between the tongue 45 and the main body portion 11' is disposed a ring 46 which is mounted on ball bearings on the portion 11^a of the plate 11'. The periphery of the ring 46 is curved. It is in fact a portion of a sphere having its center at the intersection of the axis of the cylindrical member 11^a and the central plane of the ring. It will be apparent that the ring thus forms with the casing upon which it bears, a ball and socket bearing for the plate 11'.

Referring now particularly to Fig. 7 it will be seen that the worm 20 is mounted on a shaft 47 whose lower end is journaled in ball bearings 48 and 49 and whose upper end bears a hand wheel 50. The shaft 47 passes through a packing gland 51 and ball bearings 52 are provided for reducing friction. The gear 19 is arranged to engage a series of gears 53 which are disposed symmetrically about the central axis of the large gear 19, each gear 53 being carried by a screw shaft 54 like that shown in Fig. 8. The shaft 54 has a central collar 54' ar-

ranged to enter a recess 55 (see Fig. 2). The shaft 54 is provided with a right hand screw 54^a and a left hand screw 54^b. The right hand screw extends into the frame parts 14, 15 and 16 and the left hand screw 70 is threaded into the similar parts of the siding frame on the opposite side of the plungers *i. e.*, the parts 14', 15' and 16'. It will be apparent that when the gear 19 is turned the gears 53 will all be rotated, thereby turning the screw shafts 54. Since the latter can only rotate, and has no longitudinal movement, it will draw the slideable frame members on opposite sides of the pump pistons toward and away from each other depending upon the direction in which the gear 19 is moved.

As will be seen from Fig. 3 the plate 13 is provided with an extension 13^a, which is pivotally connected with the plate 11 by 85 means of a pin 56. The plate 13' is provided with a similar extension 13^a', which is pivotally connected with the plate 11' by means of a pivot pin 56'.

From the foregoing description of the various parts of the device the operation thereof may be readily understood.

In Fig. 1 I have shown a prime mover which in this instance is an electric motor M whose shaft is connected with the shaft 95 6 of the hydraulic speed gear, which I have designated in general by S. The pipe 34 (see Fig. 3) connects the hydraulic speed gear with a hydraulic motor of any suitable type. This hydraulic motor I have designated in general by H. The pipe 32 forms a return pipe from the hydraulic motor H. The electric motor M is designed to be run at a constant speed and the revolution of the motor shaft will cause the revolution of the shaft 6 and of the plate 11 which is connected to it. The end 11^a of the plate 11 will describe a circle whose diameter will depend upon the angular relation of the line *a*—*a* which is the axial line of the cylindrical portion 11^a of the plate 11 and the line *b*—*b* which represents the axis of the shaft 6. When these two lines *a*—*a* and *b*—*b* coincide the cylindrical portion 11^a of the plate 11 will be merely revolved on its axis and the sleeve 21 will be idly revolved within the ring 24. If, however, the axis of the cylindrical portion 11^a is inclined to the axis of the shaft as shown in Fig. 3, then the sleeve 21 will be given a circular movement 115 which will cause the ring 24 to operate as a crank for reciprocating the plunger rods 25.

The stroke of the plungers 27 may be varied by turning the hand wheel 50 which, through the medium of the worm 20 and the gear 19, the gears 53, screw shafts 54, and the frame members 14, 15 and 16 and 14', 15' and 16' move the plates 13 and 13' toward or away from each other. The movement of 130

these plates toward each other when the apparatus is in the position shown in Fig. 3 would tend to bring the lines *a—a* and *b—b* nearer into alignment and would therefore shorten the stroke of the pump pistons or plungers 27. A continued movement, however, would cause the line *a—a* to intersect the line *b—b* on the opposite side of the latter and would therefore cause a reversal of 10 the movement of the pump pistons.

Referring now again to Fig. 3 it will be seen that the valve is in a position so as to permit communication to be established between the pipe 32 and one of the passages 30 leading to one of the pump cylinders, while on the opposite side the pipe 34 is in communication with one of the passages 30 leading to the pump cylinder on the opposite side of the device. The movement of the 20 pump piston 27 at the lower part of the figure will cause the fluid, which may be oil or any suitable liquid, to be drawn in through the pipe 32, chamber 31 and passage 30. The movement of the pump piston 27 at the top of the figure will force out the fluid through the passage 30 into the chamber 33 and through the pipe 34 into the hydraulic motor H. Obviously when the movement of the pump plungers is reversed 25 30 the direction of the flow of the fluid will be reversed and hence the movement of the hydraulic motor will be reversed. Similarly when the stroke of the pump plungers is greatest the flow will be fast and the hydraulic motor will be run at a greater speed. 35 As the plate 11' is shifted in accordance with the shifting of the plate 13' the cylindrical portion 11'' will be oscillated on the ring 46. The tongue 45 is disposed between 40 the lugs 41 (see Fig. 5) so that as the extension 11'' is rotated the valve will also be rotated in such a manner as to connect the pump cylinders with the pipe 32 whose pistons are traveling inwardly, *i. e.* in a direction to draw in the motive fluid and to connect the other cylinders whose plungers are traveling outwardly with the chamber 33 which is connected with the pipe 34. Therefore the fluid will be forced out of the pipe 45 50 34 through the hydraulic motor and back by the pipe 32. When the position of the pump pistons is reversed in the manner described then the fluid would be forced out through the pipe 32 through the hydraulic motor and back by the pipe 34. The speed 55 of the hydraulic motor may therefore be regulated by turning the hand wheel 50 and is, to a large extent, independent of the speed of the electric motor M.

60 It will be noted that the plate 11' serves not only as part of the means for rotating the valve, but it also acts as an auxiliary guide member for taking up end thrust which might result at the pivotal connection 65 of the companion member with the driving

means for the plungers 27, since it is on the opposite side of the driving means from the drive member 11.

The device described above forms a very efficient means of operating and controlling 70 the movements of heavy bodies such as turrets of battle ships, but it will be obvious that the device may be used for operating any kind of a machine such as an automobile truck or other similar devices. The provision of the anti-friction means for the various members insures the highest efficiency obtainable with a device of this type.

It will be obvious to those skilled in the art that various changes may be made in 80 the minor details of the invention within the scope of the appended claims and therefore I do not wish to be limited to the precise details of construction shown and described.

I claim:

1. In a hydraulic speed gear, a casing, a drive shaft rotatably carried thereby, a plurality of cylinders, the axes of said cylinders extending in radial directions from the axial line of said drive shaft, a plunger for each cylinder, a member pivotally connected to said drive shaft and having a cylindrical extension provided with a tongue, a bearing member for said cylindrical extension for permitting the pivotal movement of the pivoted member with respect to the driving shaft, said bearing member having a portion arranged to be engaged by the tongue for causing a revolution of the bearing member, and means surrounding the bearing member and movable with respect to the latter for causing the reciprocation of said plungers.

2. In a hydraulic speed gear, a gear casing, a drive shaft rotatably carried thereby, 105 a series of pump cylinders, the axis of each of said cylinders being disposed in radial relation with the axial line of said drive shaft, plungers for said cylinders, plunger rods for said plungers, an auxiliary drive 110 member pivotally connected with the end of said drive shaft, means connecting one end of said auxiliary drive member with each of said plungers for reciprocating the latter, said auxiliary drive member having 115 a pivotal movement with respect to said last named connecting means, and means for varying the pivotal relation of the drive shaft and the auxiliary drive member, said last named means comprising a member 120 movable longitudinally of said drive shaft and having a pivotal connection with a portion of said auxiliary drive member.

3. In a hydraulic speed gear, a gear casing, a drive shaft rotatably carried thereby, 125 a series of pump cylinders, the axis of each of said cylinders being disposed in radial relation with the axial line of said drive shaft, plungers for said cylinders, plunger rods for said plungers, an auxiliary drive 130

member pivotally connected with the end of said drive shaft, means connecting one end of said auxiliary drive member with each of said plungers for reciprocating the latter, said auxiliary drive member having a pivotal movement with respect to said last named connecting means, means for varying the pivotal relation of the drive shaft and the auxiliary drive member, said last named means comprising a frame slidably disposed within said casing, means for moving said slidable frame longitudinally of said drive shaft, and a plate carried by said slidable frame and having a pivotal connection with a portion of said auxiliary drive member.

4. In a hydraulic speed gear, a gear casing, a drive shaft rotatably carried thereby, a series of pump cylinders, the axis of each of said cylinders being disposed in radial relation with the axial line of said drive shaft, plungers for said cylinders, plunger rods for said plungers, an auxiliary drive member pivotally connected with the end of said drive shaft, means connecting one end of said auxiliary drive member with each of said plungers for reciprocating the latter, said auxiliary drive member having a pivotal movement with respect to the last named connecting means, means for varying the pivotal relation of the drive shaft and the auxiliary drive member, said last named means comprising a frame slidably disposed within said casing, a series of screw shafts carried by said casing and arranged to extend through said frame, a gear carried by each screw shaft, means for rotating each of said gears simultaneously to the same extent, a plate carried by said slidable frame and having an opening arranged to receive said auxiliary drive member, and an arm carried by said plate and being pivotally connected to a portion of said auxiliary drive member.

45 5. In a hydraulic speed gear, a gear casing, a drive shaft rotatably carried thereby, a series of pump cylinders, the axis of each of said cylinders being disposed in radial relation with the axial line of said drive shaft, plungers for said cylinders, plunger rods for said plungers, an auxiliary drive member pivotally connected with the end of said drive shaft, means connecting one end of said auxiliary drive member with each of said plungers for reciprocating the latter, said auxiliary drive member having a pivotal movement with respect to said last named connecting means, means for varying the pivotal relation of the drive shaft and the auxiliary drive member, said last named means comprising a frame slidably disposed within said casing, said frame having an extension, a gear loosely carried by said extension, a worm for operating said gear, a series of screw shafts carried by said

frame and arranged to extend through said slidable frame, a pinion carried by each screw shaft and arranged to mesh with said gear, a plate carried by said slidable frame and having an opening arranged to receive said auxiliary drive member, said last named plate having a movement with respect to said slidable frame in a direction at right angles to the axial line of the drive shaft, and an arm carried by said plate and having a pivotal connection with said auxiliary drive member.

6. In a hydraulic speed gear, a casing, a main drive shaft rotatably mounted within said casing, a series of pump cylinders, the axial lines of said pump cylinders being disposed in radial relation with the axial line of said drive shaft, a plunger rod for each plunger, an auxiliary drive member pivotally connected to the end of said drive shaft, means connected with one end of said drive member for causing the reciprocation of said pump plungers, a valve operating member pivotally fastened at one end to the means which connects the end of the auxiliary drive member with the pump plungers and having a pivotal connection near its opposite end with a portion of the casing, and a rotary valve having a portion arranged to be engaged by a portion of said valve operating member for rotating the valve.

7. In a hydraulic speed gear, a casing, a main drive shaft rotatably carried thereby, a series of pump cylinders, the axis of each of said cylinders being disposed in radial relation with the axial line of said main drive shaft, a plunger for each cylinder, plunger rods for said plungers, a rotary valve carried by said casing, a valve operating member pivotally connected with said casing at one end, an auxiliary drive member pivotally connected with said drive shaft at one end, an intermediate member having a pivotal connection on one side to said valve operating member and on the other side to said auxiliary drive member, means carried by said auxiliary drive member and arranged to engage said intermediate member for rotating the latter, and connections between said intermediate member and the plungers in said pump cylinders for operating the plungers.

8. In a hydraulic motor, a casing, a drive shaft rotatably mounted in said casing, a series of cylinders disposed within said casing, the axes of said cylinders being disposed in radial relation with the axial line of said drive shaft, plungers carried by said cylinders, a plunger rod for each plunger, a ring, means carried by the ring for pivotally connecting the latter with each of said plungers, a sleeve disposed within the ring and arranged to rotate with respect thereto, said sleeve having a slot, an auxiliary drive member pivotally connected with said drive

shaft and having a ball and socket connection with said sleeve, and an extension carried by said auxiliary drive member and arranged to enter the socket in said sleeve for turning the latter.

9. In a hydraulic motor, a casing, a drive shaft rotatably mounted in said casing, a series of cylinders disposed within said casing, the axes of said cylinders being disposed in radial relation with the axial line of said drive shaft, plungers carried by said cylinders, a plunger rod for each plunger, a ring, means carried by the ring for pivotally connecting the latter with each of said plungers, a sleeve disposed within the ring and arranged to rotate with respect thereto, said sleeve having a slot, an auxiliary drive member pivotally connected with said drive shaft and having a ball and socket connection with said sleeve, an extension carried by said auxiliary drive member and arranged to enter the socket in said sleeve for turning the latter, and means for varying the pivotal relation of the auxiliary drive member with said drive shaft.

10. In a hydraulic motor, a casing, a drive shaft rotatably mounted in said casing, a series of cylinders disposed within said casing, the axes of said cylinders being disposed in radial relation with the axial line of said drive shaft, plungers carried by said cylinders, a plunger rod for each plunger, a ring, means carried by the ring for pivotally connecting the latter with each of said plungers, a sleeve disposed within the ring and arranged to rotate with respect thereto, said sleeve having a slot, an auxiliary drive member pivotally connected with said drive shaft and having a ball and socket connection with said sleeve, an extension carried by said auxiliary drive member and arranged to enter the socket in said sleeve for turning the latter, means for varying the pivotal relation of the auxiliary drive member with said drive shaft, a valve operating member having a ball and socket connection with said sleeve and being provided with an extension arranged to enter the slot in said sleeve, said valve operating member having a ball and socket connection with said casing, a rotary valve carried by said casing, and an extension carried by said valve operating member and arranged to engage said valve for rotating the latter.

11. In a hydraulic speed gear, a casing, a drive shaft rotatably carried by said casing, a series of pump cylinders, the axis of said pump cylinders being disposed on radial lines with respect to the axial line of said drive shaft, plungers for said cylinders, plunger rods for said plungers, an auxiliary drive member pivotally connected to said drive shaft, a guide member similar to said auxiliary drive member pivotally connected at one end to a portion of the frame, and an

intermediate member pivotally connected with one end of said auxiliary drive member and with one end of said guide member for reciprocating said plunger rods.

12. In a hydraulic speed gear, a casing, 70 a drive shaft rotatably carried by said casing, a series of pump cylinders, the axis of said pump cylinders being disposed on radial lines with respect to the axial line of said drive shaft, plungers for said cylinders, 75 plunger rods for said plungers, an auxiliary drive member pivotally connected to said drive shaft, a guide member similar to said auxiliary drive member pivotally connected at one end to a portion of the frame, and an 80 intermediate member pivotally connected with one end of said auxiliary drive member and with one end of said guide member for reciprocating said plunger rods, the center of the pivotal connection of the auxiliary 85 drive member with said drive shaft and the center of the pivotal connection of said guide member with said casing lying in the axial line of the drive shaft.

13. In a hydraulic speed gear, a casing, 90 a drive shaft rotatably carried by said casing, a series of pump cylinders, the axis of said pump cylinders being disposed on radial lines with respect to the axial line of said drive shaft, plungers for said cylinders, 95 plunger rods for said plungers, an auxiliary drive member pivotally connected to said drive shaft, a guide member similar to said auxiliary drive member pivotally connected at one end to a portion of the frame, an intermediate member pivotally connected with one end of said auxiliary drive member and with one end of said guide member for reciprocating said plunger rods, the center of the pivotal connection of the auxiliary drive 100 member with said drive shaft and the center of the pivotal connection of said guide member with said casing lying in the axial line of the drive shaft, and means for shifting the centers of the pivotal connections of 105 said auxiliary drive member and said guide member with said intermediate member toward and away from the axial line of said drive shaft, thereby varying the stroke of 110 the plungers.

14. In a hydraulic speed gear, a casing, a drive shaft rotatably carried by said casing, a series of pump cylinders, the axis of said pump cylinders being disposed on radial lines with respect to the axial line of 120 said drive shaft, plungers for said cylinders, plunger rods for said plungers, an auxiliary drive member pivotally connected to said drive shaft, a guide member similar to said auxiliary drive member pivotally connected 125 at one end to a portion of the frame, an intermediate member pivotally connected with one end of said auxiliary drive member and with one end of said guide member for reciprocating said plunger rods, the center 130

of the pivotal connection of the auxiliary drive member with said drive shaft and the center of the pivotal connection of said guide member with said casing lying in the axial line of the drive shaft, and means for shifting the centers of the pivotal connections of said auxiliary drive member and said guide member with said intermediate

member from one side of the axial line of the drive shaft to the other side, thereby reversing the direction of movement of the plungers.

RAUL R. MORENO.
